UNITED STATES PATENT OFFICE.

HARMON BICKEL, OF FRANKLIN, PENNSYLVANIA.

PULLING-MACHINE.

No. 899,943.

Specification of Letters Patent.

Patented Sept. 29, 1908.

Application filed June 25, 1908. Serial No. 440,294.

To all whom it may concern:

Be it known that I, HARMON BICKEL, a citizen of the United States, residing at Franklin, in the county of Venango and State of Pennsylvania, have invented certain Improvements in Pulling-Machines, of which the following is a specification.

The principal objects of my present invention are to provide a pulling machine or apparatus which is composed of telescopic mast sections light in construction consistently with the required strength, for convenience in moving the apparatus from place to place and so as to provide a high mast or tower through the upper end of which the pulling rope or cable is passed for the purpose of effectually withdrawing rods, casings, etc. from Artesian and oil wells; in connection with certain mechanism for operating the pulling rope or cable, for elevating and supporting the extensible mast section, and for transporting the apparatus from place to place.

With these principal objects in view my invention consists more especially in building up the framework of the apparatus, including the mast sections, of iron beams which are formed and connected together in a particular manner so that the apparatus may be produced at a reasonable cost and will possess the maximum stability and strength required in its operation.

My invention further consists in providing the apparatus with a particular form of truck adapted for transporting the same from place to place, and which may be readily detached when the apparatus is to be set up for operation.

In the following specification I have entered into a full description of the construction, operation, and practical advantages of my invention, and what I claim as new and desire to protect by Letters-Patent is more specifically set forth in the appended claims.

In the accompanying drawings, which form a part of this specification:—Figure 1 is a front elevation of a pulling machine constructed in accordance with my invention, with the mast extended and braced in position for use. Fig. 2 is a side elevation showing the mast sections telescoped and mounted on a truck for transportation. Fig. 3 is a detail sectional view of the lower part of the mast. Fig. 4 is a plan view of the truck. Fig. 5 is a transverse sectional view

through the upper section of the mast at a point directly above the top of the lower section. Fig. 6 is a transverse sectional view through both sections of the mast.

Like numerals of reference indicate like parts in all the figures of the drawings.

Though my improved pulling machine or apparatus is designed more especially for pulling out tubes, rods, etc. from Artesian and oil wells it will be readily apparent that the same may be employed for all kinds of pulling or hoisting work where a tall mast or upright is desired for lifting articles or materials to a considerable distance above the ground or platform upon which the machine is placed; in some instances being used in the capacity of an ordinary portable derrick for building purposes.

In carrying out my present invention the lower mast section, including the supporting-frame for the drums, is made up of angle-iron or L-beams, while the upper section of the mast which telescopes within said lower section is formed of channel-iron or U-beams, whereby said mast sections are so constructed that the extensible upper section may freely slide within the lower section.

Referring to the drawings, 1 1 designate a pair of L-beams of suitable length which are arranged parallel to each other with the base-flanges projecting inward, and are connected together by flanged plates 2 bolted or riveted thereto, and these beams form the sill pieces or supporting base of the apparatus. Mounted upon these sill pieces and riveted or bolted thereto are four uprights, 3, which form the framework of the lower mast section and are composed of angle-iron or L-beams. The uprights are spaced apart at their lower ends so as to receive the drums hereinafter described, and at a suitable distance above the sill pieces the two uprights on each sill-piece are bent towards each other so that their upper portions will be closer together to receive the extensible upper section of the mast which is adapted to slide therebetween. As will be seen by the drawings the angle-beams are at the corners of the mast section and are so disposed as to form a frame rectangular in cross-section, being rigidly connected together at the lower or wider part of the mast by plates or flat bars 4 riveted thereto, and at the upper or narrower part by plates 6 and diagonal braces 7. The upper end of

this mast section is provided with front and back plates 8, and side plates 9 and 10, the latter being formed at their upper ends with ears 9^a and 10^a, respectively, for the 5 purposes hereinafter explained. The plates 8 preferably lap the edges of the side plates, and are bent over the upper ends of the uprights, (see Fig. 5) so as to form additional guides for the upper section of the mast.

10 11 designates the upper section of the mast, which is formed in the present instance of two channel-irons or U-shaped beams, spaced apart by means of blocks 12, and arranged so that the edge flanges thereof 15 will project outwardly. As will be seen by reference to Fig. 6 the upper mast section is of such size in cross-section as to fit within the upper part of the lower mast section and slide therein, and by constructing these mast 20 sections in the manner shown and described an extensible mast is provided which can be cheaply built of comparatively light material and will possess the required stability.

In the upper part of the extensible mast 25 section, between the channel-beams which comprise the same, is journaled a sheave 13, having the usual guide loops 14, and over this sheave passes the hoisting and lowering rope or cable 15. The block, as 16, at the 30 upper end of the extensible mast section is provided with a projecting tongue 17, and in said block is pivoted a bail 18 to which is attached a guy-rope 19, other guy-ropes, as 20, being fastened directly to the upper end 35 of the mast section 11 through eyes in the flanges thereof and to a loop 18^a pivoted near the upper end of the lower mast-section. Below the sheave 13 is a ring or eye 21 for doubling the lines when necessary.

40 The slideable mast-section 11 is provided near its lower end with slots 22 through which is adapted to pass a bar 23 for supporting the upper mast section in extended position, said bar being pivoted between the ears 9^a, and is adapted when swung down 45 through the slots to rest at its outer end on the upper edge of the opposite plate 10. This pivoted supporting bar is preferably located at the upper end of the lower mast, 50 as shown in the drawings, but of course may be located a short distance below the upper end of said mast. In the present instance, also, the bar extends transversely through the channel-beams, but it will be understood 55 that it may be pivoted to one of the plates 8 so as to pass between said channel-beams, and in this latter instance one of the spacing blocks 12 would be located so as to bear upon the bar and support the mast. For 60 the purpose of operating the pivoted supporting-bar 23 a pull-cord 24 is attached thereto and depends within easy reach.

The extensible mast section is raised and lowered by means of a rope 25 attached to 65 the lower end thereof and led up over a

pulley 26 journaled between the ears 10^a and extending down to a drum 27 journaled in two of the uprights or angle-beams of the lower mast section, said drum being provided with a handle 28 for turning the 70 same.

Attached to the angle-beams or uprights 3 at the front of the lower mast are two bearing boxes 29, in which is journaled a horizontal shaft 30, having its ends projecting beyond the sides of the mast for the attachment thereto of crank-handles 31. Upon this shaft between the uprights is fixed a large bull-wheel or drum 32, over which passes the drawing rope or hoisting 80 and lowering cable 15. The drum is provided at one end with a brake-wheel 33, over which passes a brake-band 34 for retarding the rotation of the drum so as to gradually lower the load which may be 85 attached to the end of the hoisting and lowering cable. The brake-band is attached at one end to the lower front cross-piece 4 of the frame, and passing over the brake-wheel is connected at its other end to a crank-shaft 90 35 mounted in a bearing-plate 36 and having a handle or operating lever 37, the bearing-plate being riveted or bolted to the front sill-piece 1. The bull-wheel or drum is also provided beyond one side of the frame with 95 a ratchet-wheel 38 engaged by a gravity-pawl 39, and this ratchet and pawl serve the usual purpose of holding the drum against backward rotation during the operation of winding the pulling rope or cable 100 thereon. The drum may be turned manually by means of the crank-handles 31, and I also provide for turning the same by horse-power, for which purpose auxiliary drums 40 are formed at the end of the bull-wheel opposite the brake-wheel, as shown in 105 Fig. 1 of the drawings.

At the center of the front sill-piece 1 is rigidly secured a plate 41, the upper end of which is formed into ears 42, spaced apart 110 to receive the rear end of the reach-bar of a carrying-truck hereinafter described, and in order to more securely connect the machine to the carrying-truck two of the plates 6 of the lower mast section are extended beyond the sides of the mast. The carrying-truck is also constructed entirely of iron, and consists of an oval-shaped frame 43 secured to an axle 44 supported by wheels 45, said frame in the present instance being 115 made up of a flat beam the ends of which terminate at the center of the forward part of the frame and are bent upwardly, as at 43^a, for attachment to a reach-bar 46 which extends longitudinally at the center 120 of the frame of the truck. The forward end of the reach-bar is twisted, as shown, for attachment to the bent ends of the frame, and the rear end of said reach-bar 125 extends some distance beyond the rear end 130

of the frame and terminates in an ear 47 which is pierced to receive a locking - pin 48. Secured upon the sides of the oval-shaped frame 43, and extending longitudinally thereon, are angle-beams 49, the vertical walls of which are disposed on a line with the outer edges of the frame, and from the ends of these angle-beams rise uprights 50, bent outwardly at their lower ends for attachment to said beams. Between the upper ends of the uprights 50 are cross-pieces 51, having upwardly bent ends by which they are firmly secured to said uprights, and so as to dispose the cross-pieces 15 below the upper ends of the uprights and form saddles in which the machine rests. These saddles are reinforced by means of inclined braces 52 extending from the cross-pieces 51 to the reach-bar 46. At the forward end of the reach-bar is an eye 53 for connecting the draft-appliance to the carrying-truck.

In the operation of the machine, for instance in drawing a tube from an oil-well, it is set up in front of the well and the upper mast extended or raised by turning the drum or windlass 27 until the latch-bar 23 falls through the slots 22 to position across the top of the lower mast, after which the drum 27 is permitted to turn slowly backward to lower the upper mast until it rests upon the latch-bar, the latter then engaging the upper walls of the slots 22. This provides a very tall mast which is properly braced by securing the guy-ropes to stakes in the usual manner. The machine is then ready for operation, and the pulling rope or cable which is wound upon the large drum 32 and extends up over the sheave 13 is attached to the tube in any suitable manner, and by turning the drum, either manually or by horse-power, the tube may be withdrawn, the height of the mast permitting a considerable length of the tube to be withdrawn at each operation. In lowering a tube or other load the unwinding of the rope or cable 15 is effected gradually by applying the brake-band through the intervention of the operating lever 37.

50 In moving the machine from one place to another the upper section of the mast is lowered by first elevating it a slight distance to permit the latch-bar 23 to be raised, and then said mast section is slowly lowered by operating the drum or windlass 27. The carrying-truck is moved to position in front of the telescope mast and connected to the lower end thereof by passing the ear 47 at the end of the reach-bar of the truck between the 55 ears 42 on the attaching plate 41, and inserting the locking pin through the ears. The telescoped mast is then tilted forward on to the truck into the saddles and so that the extended ends of the plates 6 will engage 60 the forward edges of said saddles, the tele-

scoped mast assuming a horizontal position, as shown in Fig. 2, so that it may be carried by the truck. The machine may be hauled by horses or other draft animals by attaching a draft-bar to the forward end of the 70 reach-bar of the carrying truck, and passing the ring of the neck-yoke over the projection or tongue 17 at the outer end of the extensible section of the mast.

As hereinbefore stated, the particular construction of the parts provides a mast that can be cheaply built of comparatively light material, can be conveniently moved from place to place and easily and quickly set up for operation, and in use provides a tall mast 75 possessing the required strength and stability.

It will be understood that the angle-beams which form the uprights of the lower or stationary mast section may be connected by plates alone, or by diagonal braces alone, but 80 the employment of both arranged in the particular manner shown provides a very rigid structure rectangular in cross-section to receive the channel-bars forming the upper section, and so that when said upper section 90 is extended the lower end thereof will be firmly supported in the upper end of the lower or stationary section of the mast.

As shown in Fig. 6 the diagonal braces 7 may be located at the inner side of the lower 95 mast-section within the channel-bars so as to permit the latter to bear directly against the angle-irons, while the plates 6 at the front and rear of the lower mast-section may be secured to the outer side thereof.

Having thus described my invention, what I claim is:—

1. In a pulling machine, a lower mast section comprising sill-pieces, angle-bars secured thereon in upright position with their 105 walls disposed to form a structure rectangular in cross-section, and means as plates connecting the angle bars; together with an extensible mast section slidable between the angle-bars, and means for supporting the extensible mast section in raised position.

2. In a pulling machine, a lower mast section comprising sill-pieces, angle-bars secured thereon in upright position and having their walls disposed to form a structure 115 rectangular in cross-section, and plates connecting the angle-bars; together with an extensible mast section composed of channel-bars connected together and adapted to slide within the lower mast section, and means for supporting the extensible mast section in raised position.

3. In a pulling machine, a lower mast section comprising sill-pieces and connected angle-bars secured thereon in upright position 125 with their walls disposed to form a structure rectangular in cross-section, an extensible mast section slidable within the lower mast section and composed of channel-bars connected together with their edge 130

flanges projecting outwardly, and means for supporting the extensible mast in raised position.

4. In a pulling machine, a lower mast section comprising angle-beams forming sill-pieces, angle-bars secured in upright position upon the angle-beams and having their walls disposed to form a structure rectangular in cross-section, plates connecting the angle-bars together, an extensible mast section slidable within the lower mast section and composed of channel-bars connected together with their edge flanges projecting outwardly, and means for supporting the extensible mast section in raised position.

5. In a pulling machine, a lower mast section comprising angle-beams forming sill-pieces, angle-bars secured thereon in upright position with their walls disposed to form a structure rectangular in cross-section, said angle-bars being spread apart at their lower ends to form a frame wider than the body of the mast, an extensible mast section slidable in the upper part of the lower mast section, a sheave in the upper part of the extensible mast section, and a drum mounted in the lower part of the lower mast section, substantially as shown and for the purpose set forth.

30 6. In a pulling machine, a lower mast section comprising angle-beams forming sill-pieces, angle-bars secured thereon in upright position with their walls disposed to form a structure rectangular in cross-section, said angle-bars being spread apart at their lower ends to form a frame wider than the upper part of said mast section, an extensible mast section slidable within the upper part of the lower mast section and having a slot near its 35 lower end, a bar pivoted to the upper end of the lower mast section and adapted to pass through the slot and support the extensible mast section in raised position, and means for raising the extensible mast section, substantially as shown and described.

40 7. In a pulling machine, a lower mast section comprising angle-beams arranged parallel to each other to form sill-pieces, angle-bars secured thereon in upright position with their walls disposed to form a structure rectangular in cross-section, said angle-bars being spread apart at their lower ends to form a frame wider than the upper part of the mast, plates connecting the angle-bars 45 together, an extensible mast section slidable within the upper part of the lower mast section and composed of channel-bars and interposed blocks, said channel-bars being arranged with their edge flanges projecting outwardly, a sheave journaled between the upper ends of the channel-bars of the extensible mast section, a bull-wheel journaled in the frame of the lower mast section, and a pulling rope wound upon the bull-wheel and 50 extending up over the sheave; together with

means for supporting the extensible mast section in raised position.

8. In a pulling machine, a lower mast section comprising angle-beams forming sill-pieces, angle-bars secured thereon in upright position with their walls disposed to form a structure rectangular in cross-section, said angle-bars being spread apart at their lower ends to form a frame wider than the upper part of the mast section; an extensible mast section slidable within the upper part of the lower mast section and composed of channel-bars and interposed spacing blocks, said extensible mast section being provided with a transverse slot near its lower end, a bar pivoted to the upper end of the lower mast section and adapted to extend through the slot to support the upper section in raised position, a sheave journaled between the upper ends of the channel-bars, a bull-wheel journaled in the lower end of the lower mast section and having a pull rope wound thereon and extending therefrom over the sheave, a windlass in the lower part of the lower mast section, and a rope extending from the windlass up over the upper end of the lower mast section and secured to the lower end of the upper mast section, substantially as shown and described.

9. In a pulling machine, a lower mast section comprising sill-pieces, angle-bars disposed thereon in upright position with their walls disposed to form a structure rectangular in cross-section, plates secured to the front and back of the mast to connect the angle-bars, diagonal braces secured within the sides of the mast, an extensible mast section bull-wheel in the lower part of the lower mast section and composed of channel-bars connected together with their edge flanges projecting outwardly and towards the sides of the lower mast section, a sheave in the upper part of the extensible mast section, a bull-wheel in the lower part of the lower mast section, and a pull-rope wound upon the bull-wheel and extending over the sheave, together with a latch bar at the upper end of the lower mast section adapted to support the upper mast section in raised position, and means for raising the upper mast section.

10. In a pulling machine, a lower mast section comprising angle-beams arranged parallel to each other with their base flanges projecting inwardly, angle-bars secured in upright position upon the angle beams with their walls disposed to form a structure rectangular in cross-section, said angle-bars being bent apart at their lower ends to provide a frame wider than the upper part of the mast section, plates connecting said angle beams together; an extensible mast section slidable in the upper part of the lower mast section and composed of channel-bars with interposed spacing-blocks, said channel

beams being arranged with their edge flanges projecting outwardly, a bar pivoted upon the upper end of the lower mast section and adapted to extend across the top of 5 said lower mast section through the lower part of the extensible mast section, a pull-cord attached to said pivoted bar, and means for raising and lowering the extensible mast section; together with a bull-wheel mounted 10 in the lower parts of the lower mast section, a sheave mounted in the upper part of the extensible mast section, and a pulling rope or cable wound upon the bull-wheel and extending over the sheave, substantially as 15 shown and described.

11. In a pulling machine, a telescoping mast comprising a lower mast section formed of sill-pieces and angle-bars secured thereon in upright position, and an extensible mast 20 section slideable in the upper part of the lower mast section and composed of channel-bars, a drum mounted in the lower part of the mast and having a brake-wheel at one end, a brake-band on said brake-wheel se- 25 cured at one end to the mast and a crank-shaft to which the other end of said brake-band is connected, a sheave at the upper end of the mast, and a pulling rope or cable wound upon the drum and extending over the 30 sheave; together with means for raising the

extensible mast and for supporting the same in raised position.

12. In a pulling machine, the combination, of a telescoping mast comprising a lower section formed of sill pieces and angle-bars 35 secured thereon in upright position and an extensible upper section slideable in the lower section and composed of channel-bars, a drum in the lower part of the mast, a sheave at the upper end thereof, a pulling 40 rope or cord wound upon the drum and extending over the sheave, plates attached to the front of the lower mast section and extending beyond the sides thereof, and a plate secured to the front sill piece and having 45 ears at its upper end; together with a carrying-truck having saddles to receive the lower mast section and engage the extended ends of the plates, and an extended reach bar having an ear at its rear end adapted to 50 enter between the ears of the plate on the sill piece, said ears receiving a locking-pin, substantially as herein shown and described.

In testimony whereof I have signed my name to this specification in the presence of 55 two subscribing witnesses.

HARMON BICKEL.
